TRANSPARENT COVERING PANEL FOR LIGHT FITTINGS

Friedrich Clostermann, Hagen, Germany, assignor to
Trilux-Lenz KG, Neheim-Hüsten, Germany

Original design application July 11, 1969, Ser. No. 18,174,
now Patent No. 221,176, dated July 13, 1971. Divided
and this application June 18, 1970, Ser. No. 24,102

Term of patent 14 years

Int. Cl. D26—05

U.S. Cl. D48—16

FIG. 2

FIG. 1 is a top plan view of a transparent covering panel for light fittings showing my new design,

FIG. 2 is a side elevational view thereof taken in the direction of the arrow 2 in FIG. 1, and

FIG. 3 is a side elevational view thereof taken in the direction of arrow 3 in FIG. 1.

This is a division of design application Ser. No. D. 18,174, filed July 11, 1969, now Design Pat. 221,176. I claim:

The ornamental design for a transparent covering panel for light fittings, as shown.
